UNITED STATES PATENT OFFICE.

DAVID E. CARLSON, OF GALESBURG, ILLINOIS.

VALVE-SPRING LIFTER.

Application filed July 22, 1921. Serial No. 486,824.

To all whom it may concern:

Be it known that I, DAVID E. CARLSON, a citizen of the United States, residing at Galesburg, in the county of Knox and State 5 of Illinois, have invented new and useful Improvements in Valve-Spring Lifters, of which the following is a specification.

This invention relates to tools of the movable jaw type and an object of the invention 10 is to provide a tool which is particularly adapted for use in lifting springs such as used upon the valves of internal combustion engines, the said tool being designed to easily compress or lift the springs of valve stems 15 to permit the ready and easy removal of the valves associated therewith.

Another object of the invention is to provide a tool wherein the leverage of the respective movable jaws is designed to permit 20 the raising or compressing of the valve springs with a minimum effort.

Other objects of the invention will appear in the following detailed description and in the accompanying drawings wherein:

25 Fig. 1 is a side elevation of the improved valve spring lifter or compressor showing it in its closed position in solid lines and its open or valve spring compressing position in dotted lines.

30 Fig. 2 is a plan of the improved tool.

Fig. 3 is a section on the line 3—3 of Fig. 1.

Referring more particularly to the drawing the improved tool comprises handles 1 and 2 each of which comprises a relatively long hand grip portion 3 and a relatively short jaw carrying portion 4 which extends at an acute angle to the hand grip portion 3 so that when the hand grip portions 3 are 35 spread as shown in solid lines in Fig. 1 of the drawing the jaw carrying portions 4 will lie substantially in parallelism, the same being true of the hand grip portions 3 when the jaw carrying portions 4 are spread as 40 shown in dotted lines in Fig. 1 of the drawing.

The handles 1 and 2 are connected at the junction of the portions 3 and 4 by links 5 which are attached to the opposite sides of 45 the handles as shown in Fig. 1 of the drawing. The facing sides of the handles, at their point of connection, are concavely cut-out and receive therein a roller 6 which is rotatably supported on a suitable pin 7 carried by the plates 5 permitting the free unimpeded pivotal movement of the handles.

The jaw carrying portions 4 have the jaw arms 8 pivotally connected to their outer ends as shown at 9 and the jaw arms 8 each have transversely extending extensions 10 formed thereon which engage upon opposite sides of the portions 4. The jaws proper 11 are flat and formed integrally with the arms 8, and are bent so that they will always lie parallel one to the other and move either 15 towards or away from each other in straight lines and in parallel relation. The said movement is accomplished through the medium of the arms 8 and links 12 which are pivotally connected to the arms 8 and to the 20 hand grip portions 3 of the handles 1 and 2. The hand grip portions 3 are provided with a plurality of spaced openings 13 any one of which in each handle is adapted to receive the pivot pins 14 of the links 12 to 25 permit adjustable connection of the links 12 with the handles 1 and 2 and consequently adjustment of the relation of the jaws 11 and arms 8 relative to the handles. The jaws 11 are provided with cutout portions 15 adapted 30 to engage about a valve stem to permit proper engagement of a valve spring to be lifted or compressed.

By reference to the drawing it will be 35 noted that the links 12 are connected to the hand grip portions of the handles 1 and 2 most remote from the arms 8 to which they are connected.

It is, of course, to be understood that the invention may be constructed in various 40 other manners and the parts associated in different relations and, therefore, I do not desire to be limited in any manner except as set forth in the claims hereunto appended.

Having thus described my invention what 45 I claim is:

1. In a valve spring lifter, a pair of handles which comprise hand grip portions and jaw carrying portions extending at acute angles to the hand grip portions, links connecting said handles, said handles being recessed adjacent their points of connection, a roller engaging in said recesses, and jaws carried by said handles.

2. In a valve spring lifter, a pair of handles which comprise hand grip portions and jaw carrying portions extending at acute angles to the hand grip portions, links connecting said handles, said handles being recessed adjacent their points of connection, a roller engaging in said recesses, jaw arms pivotally connected to said handles, jaws

formed thereon, and links pivotally connected to said arms, and said handles whereby said jaws will always move in parallel relation upon movement of said handles.

5. 3. In a valve spring lifter, a pair of handles, each comprising a hand grip portion and a jaw carrying portion extending at an acute angle to the hand grip portion, means pivotally connecting said handles at the 10 junction of said hand grip and jaw carrying

portions, jaws pivotally connected to the outer ends of said jaw carrying portions, arms on said jaws and extending beyond the connection of said handles, and links pivotally connected to said arms and pivotally 15 and adjustably connected to said hand grip portions.

In testimony whereof I affix my signature.

DAVID E. CARLSON.
